CLAIM

The ornamental design for a laundry appliance console, as shown and described.

DESCRIPTION

FIG. 1 is a right front perspective view of the laundry appliance console;

FIG. 2 is a front elevational view thereof. The ornamental design is not visible in a rear view;

FIG. 3 is a right side elevational view thereof, the left side elevational view being a mirror image; and,

FIG. 4 is a top plan view thereof. The ornamental design is not visible in a bottom view.

The broken line showing of mechanical indicators is included for the purpose of illustrating portions of the laundry appliance console and forms no part of the claimed design.
